UNITED STATES PATENT OFFICE.

CLARENCE E. BEACH, OF BINGHAMTON, NEW YORK.

SIGNAL SYSTEM.

Application filed November 3, 1919. Serial No. 335,430.

To all whom it may concern:

Be it known that I, CLARENCE E. BEACH, a citizen of the United States, residing at Binghamton, county of Broome, and State of New York, have invented certain new and useful Improvements in Signal Systems, of which the following is a specification.

This invention relates to electrical signal systems employing a plurality of conductors, and is particularly adapted for use in systems employing such conductors in varying combinations,—such as, for example, emergency signal systems provided for fire alarm, night watch and similar service, and comprising a central station having suitable current supply and manifesting mechanism, a plurality of distant signal initiating stations having circuit-breaking and circuit-grounding mechanism, and a normally closed line-circuit in which such stations are connected.

Systems have heretofore been devised in which manually or automatically operable switches were provided whereby, in case of grounding, breaking or crossing of the line wires of such a circuit, the stations on both sides of the break or ground may be quickly placed in operative connection with the central station instruments,—and other systems have heretofore been devised in which duplicate signal manifesting mechanisms were provided at the central station, connected in the respective sides of such a circuit, so that, in the event of concurrent activity of any two initiating stations, the signals of such stations could be independently and correctly manifested by such respective central station mechanism; but none of such prior systems have been dependably responsive, without readjustment, under either normal or any of said abnormal conditions.

It is a well recognized fact that the current paths of signal systems intended to give notification or warning of emergencies are likely to be subjected to progressive impairment incident to the development of such emergencies, and that the likelihood of concurrent activity of a plurality of the initiating stations of such a system increases with the gravity and proportions of an emergency. In view of these facts,—it is highly important that no signal shall be lost through successive or simultaneous development of such circuit conditions, even though the activity of an initiating station is inter-

rupted and all connection between such station and the central station is destroyed prior to any repetition of its signal.

If such losses are to be avoided, operability under normal conditions must be attained without recourse to either automatically or manually operable switches which require adjustment subsequent to the development of abnormal conditions, as, by the very nature of such switches, correct response to intended signal impulses is impaired pending, and incident to, readjustment of such switches following the development of abnormal conditions. Furthermore, responsiveness of such automatic switches depends upon delicate instrument adjustments, the effectiveness of which cannot be readily verified; and manual switches are not used with sufficient frequency to enable attendants to become desirably proficient in their timely adjustment.

Signal systems, such as those hereinbefore referred to, frequently comprise circuits of comparatively low insulation and high conductor resistance; thus limiting the electro-motive force of the current source, and hence the line current flow, to comparatively low values; while permitting substantial current leakages under certain atmospheric conditions. In order to assure dependable response of the central station manifesting mechanism to the initiating stations of such systems, it is therefore needful that such mechanism shall be responsive to comparatively small changes in the strength of the current flow in the signal circuit, and that the current changes incident to signals from initiating stations under either normal or abnormal conditions shall be such as to assure the intended response.

It is well recognized that the development of an unintended ground connection, or an excessive leakage between line conductors and the ground, is detrimental to the dependable operability of any electrical signal system, and it is therefore desirable to promptly detect and give suitable warning of such conditions. Various constant test arrangements have heretofore been devised for the purpose of assuring such detection and warning, but the employment of such prior arrangements has incurred opportunities for losses of signals which have been deemed more objectionable than those likely to arise in the absence of such arrangements from

the ground connections or leakage they might detect. Such incurred opportunities have been found to be particularly objectionable in instances of systems which are, 5 at times, unattended by anyone qualified to make suitable readjustment of the operating conditions, in the event of the development of an unintended ground connection or leakage such as might so co-operate with the 10 ground connection employed by the testing arrangement as to impair the operability of the signal circuit to which it was applied.

The main object of this invention is to provide a signal system comprising three or 15 more conductors, and having constantly effective means whereby the interconnection of any two of such conductors will establish a signal current path operatively independent of any connections existing between 20 such two conductors and the other conductor or conductors of such system.

Another object of this invention is to provide means whereby the development of a ground leak in a normally ungrounded signal circuit may be instantly manifested, 25 without thereby impairing the effectiveness of such signal circuit.

Another object of this invention is to provide a signal system comprising a series 30 circuit connecting central office manifesting and current supply mechanism with a plurality of initiating stations so that facilities will be provided, without readjustment, for the complete and correct manifestation 35 at the central station of signals from all actuated initiating stations either when the conductors and apparatus of such system are in normal condition or when such conductors and apparatus are subjected to any 40 of the following abnormal conditions: series circuit broken at any one or between any two initiating stations; circuit grounded at any one or between any two initiating stations; line wires crossed so as to shunt out 45 any one, more or all initiating stations; broken ground connection at any initiating station or stations; concurrent activity of any two initiating stations; concurrent activity of any two initiating stations while 50 the circuit is broken or grounded between such stations; line wires crossed at opposite sides of one, more or all initiating stations and broken at any one point; or line wire broken and direct current difference 55 of earth potential between the central station ground connection and the ground connection of an active initiating station substantially equivalent to that of the signal circuit current source.

60 Other objects of this invention will be in part obvious and in part specifically set forth in the following specification.

In constructing this invention, electromotive forces differing in phase from one 65 another are provided for the energization

of respective signal circuit current paths. Thus, in the instance of a normally closed metallic circuit from which signals should be received in response to either circuit-breaking or circuit-grounding, three such 70 electromotive forces should be provided.

In any event, there should be at least as many such electromotive forces as there are opportunities for establishing signal circuit current paths, the operability of each of 75 which should be instantly effective. Thus in a system having four such conductors (one of which may be the ground), at least four of such electromotive forces should be available. 80

It should be distinctly understood that the word "phase" as employed throughout these specifications in defining a difference between various electromotive forces, is used in a broad sense which not only includes 85 the meaning ordinarily intended when this word is employed in referring to electrical circuits and appliance of various polyphase systems which develop two or more electromotive forces differing in phase from one 90 another by a constant angle,—but, as herein employed, the word "phase" is intended to include any recurrent difference between two or more developed electromotive forces, regardless of whether or not such electromotive forces are equal in effective value, 95 regardless of whether they are subject to corresponding variations, and regardless of whether they differ in phase in corresponding degrees. 100

For example,—what is ordinarily termed a "single phase" alternating current source is capable of such utilization in accordance with this invention that it will provide two electromotive forces differing in phase from one another, in the broad sense in which the subject of phase relation is herein treated. 105

For further example,—it should be noted that, under certain circumstances, one 110 or more direct current sources can be so employed that, through the co-operation of pole-changers, distributors, interrupters or other similar instrumentalities, or by suitable interconnection between direct current and alternating current sources, pulsations may be periodically applied to several conductors in orderly sequence, or may be applied to some of such conductors so that the current flow in other of such conductors 115 may or may not be thereby influenced, depending upon the existing connections therebetween. 120

For the purpose of facilitating the understanding of this invention, and for the further purpose of setting forth in greater detail certain features thereof, a number of embodiments are illustrated in the accompanying drawings and hereinafter more 125 fully described. 130

Like reference characters denote similar parts throughout the accompanying drawings in which,—

5 Figure 1 is a diagrammatic representation of a signal system provided with a three-phase open-delta current supply utilized in accordance with this invention.

10 Figs. 2 and 3 illustrate applications of three-phase closed-delta and star or Y-connected current supply for the system shown in Fig. 1.

15 Fig. 4 illustrates the application of a so called "single-phase" alternating current source to such a signal system as that shown in Fig. 1.

20 Fig. 5 illustrates a means of co-operatively employing direct and alternating current sources, in accordance with this invention, for the operation of a signal system such as that shown in Fig. 1.

25 Fig. 6 illustrates a means, differing somewhat from that shown in Fig. 4, for supplying energy from a single-phase alternating current source for the operation, in accordance with this invention, of a system such as that shown in Fig. 1.

30 Fig. 7 illustrates an arrangement for utilizing through the co-operation of a pole-changer, a direct current source such as a battery, for the operation in accordance with this invention of such a signal system as that shown in Fig. 1.

35 Figs. 8 and 9 are enlarged representations of details of the mechanism at the initiating stations of Fig. 1, showing the parts in normal and abnormal conditions, respectively.

40 Referring to Fig. 1,—A¹ diagrammatically indicates a three-phase alternating current generator of suitable frequency, to the terminals of which the primary coils 21 and 22 of suitable transformers are connected through proper line conductors in so-called "open-delta". The coils 23 and 24 are the 45 secondary windings of the transformers excited by the primary coils 21 and 22, respectively. One lead from the secondary coil 23 connects with the terminal 25, one lead from the secondary coil 24 connects with the terminal 27, and a lead from the remaining ends of the coils 23 and 24 connects with the terminal 26.

50 From the foregoing it will be apparent that electromotive forces will be developed for three current paths i. e. between terminals 25 and 26, between terminals 25 and 27, and between terminals 26 and 27; that such electromotive forces will be developed in such respective current paths in an orderly 55 sequence, will be substantially equal in effective value, and will therefore provide means for the energization of suitable electromagnets upon the connection of any such magnet between any two of said terminals.

55 In the utilization of these electromotive

forces, the relays B, C and D each have one terminal thereof connected to the terminals 25, 26 and 27, respectively, said relays being so constructed as to be suitably responsive to current flow of the frequency produced by the generator A¹. The remaining terminals of relays B and D are connected with the central office line-wire terminals 28 and 29, respectively, and the remaining terminal of relay C is connected to the ground.

A three-pen register is diagrammatically indicated at E, comprising the paper tape roll 30, the free end 31 of which passes under the marking ends of the pens 32, 33 80 and 34. Said pens are independently operable for the purpose of suitably marking upon the tape 31 in response to energization of the actuating magnets 35, 36 and 37, respectively.

85 A suitable register battery 38 is shown, one terminal of said battery is connected to the armatures of the relays B, C and D, and the other terminal of said battery is connected to one of the leads of each of the magnets 35, 36 and 37. The remaining leads of magnets 35 and 37 are connected to the back contacts of relays B and D, respectively, and the remaining lead of magnet 36 is connected to the front contact of relay C.

90 It is assumed that there will be suitable propelling means for the paper tape 31, but, as pen registers embodying such means are well understood by those skilled in this art, and as the detailed construction of the registering mechanism forms no part of this invention, further illustration or description of same is omitted in the interests of clearness and brevity.

95 Suitable initiating stations, such as F, G, H, I and J, are shown serially connected between the central office terminals 28 and 29: the station H being shown on an enlarged scale, so as to facilitate illustration of the 100 code-wheel 39, normally closed contacts 40 and 41, and the normally open ground contact 42 thereof.

105 The code-wheel 39 is so formed that, when at rest, the contact 40 is held in conductive relation with the contact 41, but said contacts are not raised high enough to bring the contact 41 in conductive relation with the contact 42. During the rotation of the code-wheel 39, each tooth first raises the contacts 40 and 41 so as to bring them into conductive relation with the contact 42, and then allows all of said contacts to separate one from another, thus providing circuit-breaking and circuit-grounding mechanism.

110 120 125 Suitable means, such as a manual operating handle 43, is provided for causing the actuation of the code-wheel 39.

130 It should be understood that mechanism comprising corresponding instrumentalities

is provided at the initiating stations F, G, I and J.

The operation of the embodiment of this invention illustrated by Fig. 1 is as follows:

Under normal conditions, the ground contacts 42 of the initiating stations F, G, H, I and J are electrically isolated from the contacts 40 and 41 associated therewith; hence the ground connections of the signal initiating stations are not effective, the relay C will be de-energized, its armature will occupy its retracted position as shown, and register magnet 36 will be de-energized. The line breaking contacts 40 and 41 of each of the initiating stations will stand closed, and there will be an alternating current flow, through the normal or line circuit current path, which flow will 20 suitably energize relays B and D and thereby hold the armatures of these relays against their front stops, as shown, thereby causing the de-energization of magnets 35 and 37.

The normal current path just referred to, extends from one lead of secondary coil 23 through conductor 51 to terminal 25; thence through conductor 52, relay B, and conductor 53, to the central office terminal 28; thence through conductor 54 to left-hand terminal station F; thence through conductor 55 of said station (as illustrated at station H) to contact 40 thereat; thence through contact 41 and conductor 56 to the right-hand terminal of station F; thence through conductor 57 to the left-hand terminal of station G, and correspondingly through station G to the right-hand terminal thereof; thence through conductor 58 to the left-hand terminal of station H and correspondingly through said station to the right-hand terminal thereof; thence through conductor 59 to the left-hand terminal of station I and correspondingly through said station to the right-hand terminal thereof; thence through conductor 60 to the left-hand terminal of station J and correspondingly through station J to the right-hand terminal thereof; thence through conductor 61 to the central office terminal 29; thence through conductor 62, winding of relay D and conductor 63 to terminal 27; thence through conductor 64 to secondary coils 24 and 23 acting in series.

While the coils 23 and 24 are thus acting in series, it is evident that a so-called "single-phase" alternating current will flow between terminals 25 and 27, which current flow will be of substantially the same effective strength as if either coil 23 or coil 24 was acting alone.

If now the code-wheel 39 of any initiating stations should be set in motion, as by the actuation of the operating handle 43 associated therewith, said wheel will first

bring the contacts 40 and 41 into conductive relation with the ground contact 42 associated therewith, and will then permit said contacts to move away from one another; after which the contact 40 will be again moved into conductive relation with contacts 41 and 42 by the next tooth of the code-wheel 39, and this cycle of operation will be repeated such number of times and at such intervals as to formulate the desired code signal.

Upon the establishment of a conductive relation between contact 42 and the contact 40 and 41 of any initiating station, as just described, a current flow will be established through relay C, so as to cause the effective energization thereof, and thereby cause the energization of register magnet 36 to actuate register pen 33, which current flow will traverse the following divided path; from terminal 26, through conductor 66, winding relay C and conductor 67 to ground at 68, thence through the earth to the ground associated with the station the code-wheel 39 of which is being operated. Assuming, for convenience, that the code-wheel of station H is being operated, the current from ground 68 will leave the earth at ground 71, and pass through conductor 79 to the middle terminal of station H, thence through conductor 78 of said station to contact 42 thereof. From contact 42, of the actuated station, two current paths will be provided as follows: one path through contact 41, and conductor 56 to the right-hand terminal of said station; thence through conductor 59, station I, conductor 60, station J, conductor 61, terminal 29, conductor 62, relay D, conductor 63, terminal 27, conductor 64, secondary coil 24 and conductor 65 to terminal 26; and the other path through contact 40 and conductor 55 to the left-hand terminal of station H; thence through conductor 58, station G, conductor 57, station F, conductor 54, terminal 28, conductor 53, relay B, conductor 52, terminal 25, conductor 51, secondary coil 23 and said conductor 65 to terminal 26.

It is evident that while this divided current path is effective, as just described, the effectiveness of the energization of relays B, C and D will be substantially equal; hence throughout the periods when the ground connection of any initiating station is effective, the armature of the relay C will move to attracted position, and the armatures of relays B and D will remain in their normal attracted positions.

Whenever the contact 40 of any initiating station drops into a notch of the code-wheel 39 co-operating therewith, said contact 40 will move away from the contact 41, and the contact 41 will, at the same time, move away from the contact 42, thus breaking the ground connection and interrupting all cur-

rent flow through the relays B, C and D, and thereby permitting the armatures of said relays to move to retracted position.

The retractive movement of the armatures of relays B and D will cause energization of the register magnets 35 and 37, and the corresponding movement of the armature of relay C will cause the de-energization of the register magnet 36.

10 Continued rotation of the acting code-wheel 39 will thereafter move the contact 40 associated therewith into conductive relation with its cooperating contact 41, and thereafter move said contacts 40 and 41 into 15 conductive relation with their associated contact 42. Such conductive relationship between contacts 40 and 41 will serve to re-establish current flow through the normal current path already described, thereby reenergizing relays B and D, which relays will thereupon act to cause deenergization of register magnets 35 and 37; and such conductive relationship between contacts 40 and 20 41 and contact 42 will serve to re-establish 25 current flow through the ground path as hereinbefore described, so as to cause re-energization of relay C, which relay will then act to cause reenergization of register magnet 36.

30 From the foregoing it will be apparent that, when all current paths are in proper condition, the actuation of any initiating station will cause its code signal to be recorded concurrently by pens 32, 33 and 34, 35 although the record produced by the pen 33 will be somewhat advanced, in point of time, from records produced by pens 32 and 34.

Should the signal circuit be broken, as, for example, at 80, relays B and D will be 40 de-energized, and register magnets 35 and 37 will be energized, thus giving the intended warning of such a break.

If any initiating station is actuated while the normal current path is interrupted, as 45 by a break at 80, the relay C and either the relay B or the relay D, as the case may be, will be energized during each of the periods when the contacts 40 and 41 of such station are brought into conductive relation with the co-operating contact 42, and the code 50 signal of such station will therefore be manifested by the pen 33 and by either the pen 32 or the pen 34.

During any signal, such as just described, 55 if any initiating station located at the other side of such a break is actuated, the pen 32 will manifest the signal of one of said stations and the pen 34 will manifest the signal of the other of such stations, while the pen 33 will produce a record comprising the code signals of both of such stations.

Should the code-wheel of any station be brought to rest in a position which presents a notch to its contact 40, thereby interrupting the normal current path through

such station, it is evident that the defective condition of such station will be correspondingly manifested, and that, pending the repair thereof, the signal of any station connected at either side of such defective station, or of any two concurrently acting stations connected at opposite sides of such defective station, will be correctly manifested in the manner already pointed out.

Should an accidental leakage to the ground 75 develop, as suggested by the dotted line 81, such leakage will result in current flow through the winding of the relay C, and the energization of said relay will cause the actuation of pen 33 to manifest such defect. 80 If any initiating station should be actuated during the continuance of such a ground leak, the signal of such station will cause responsive action of the relay B or the relay 85 D (depending upon the position of the actuated station in the circuit with relation to such leak) and thereby cause either the pen 32 or the pen 34, as the case might be, to manifest the code signal of such initiating 90 station.

While a station connected at one side of such a leak is acting, if a station connected in the circuit at the opposite side of such a leak is actuated, the code signals of both of such stations will be correctly manifested, 95 one of said signals being manifested by the pen 32 and the other of said signals being manifested by the pen 34.

Should the code-wheel of any initiating station come to rest in a position which renders the ground connection thereat effective and any other initiating station be actuated during such effectiveness, or should two other initiating stations connected at opposite sides of such grounded station be 105 concurrently actuated, the code signal or signals of such station or stations will be correspondingly manifested.

It is evident that should the code-wheel of any station come to rest either in a position which renders the ground connection effective or in a position which breaks the normal signal current path, the actuation of such station will nevertheless cause its code signal to be correctly manifested by the 115 register E.

Should the line wires become crossed, so as to shunt out any one or more initiating stations, as suggested by the dotted line 82; or should the normal current path be short-circuited, as suggested by the dotted line 120 83 between the central office terminals 28 and 29, no immediate warning would be given by the central office equipment (unless such shunt included a ground connection).

While any station or stations, or the entire normal current path is short-circuited, as just described, if any initiating station is actuated, upon each occasion when the 130

6
ground connection of such station is made effective by the operation of the code-wheel thereat, the relay C will be energized, and the pen 33 will therefore be caused to manifest the signal of such station. Under these circumstances the pens 32 and 34 will not respond.

Should the ground connection be broken at any initiating station, as, for example, 10 by the disconnection of the ground wire from the central terminal thereof, the actuation of said station will cause the de-energization of relays B and D, and hence will cause pens 32 and 34 to manifest the signal 15 of such station.

Although no immediate warning is given of the short-circuiting of all or any part of the normal current path, and although no immediate warning is given of a break 20 in the ground connection of any initiating station,—it is evident that notification of such defects will be provided in the following manner. If a signal initiating station is actuated while the normal line current 25 path therethrough is short-circuited, the signal of such station will be manifested exclusively by the pen 33, and the failure of the pens 32 and 34 to concurrently act will serve to indicate that the normal current 30 path through such station is short-circuited. When a signal is received from any station the ground connection of which is interrupted, such signal will be manifested by pens 32 and 34, but the pen 33 will not act 35 in response thereto; and the failure of said pen 33 to act concurrently with the pens 32 and 34 will serve to indicate that the ground connection of such station is defective.

If any two signal stations are simultaneously actuated at a time when all current 40 paths are in normal working order, the signal of one of such stations will be manifested by the pen 32 and the signal of the other of such stations will be manifested by the pen 34; and the pen 33 will respond to 45 all impulses of both stations; so that the signals of such stations will be manifested by the pens 32 and 34, respectively without interference.

From the foregoing it will be evident that 50 when the pens 32, 33 and 34 are acting concurrently, the relay B and the pen 32 will act responsively to some one initiating station, and the relay D and pen 34 will act 55 in response to the same or some other one initiating station but, during the concurrent actuation of two or more initiating stations, neither of said relays or pens will act in response to the impulses of more than one 60 of such stations. On the other hand,—inasmuch as the relay C and pen 33 will act in response to the impulses to which both relay B and relay D are subjected when two or more signal stations are acting concurrently,—it is desirable that when all of the 65

pens are acting concurrently, the code signals shall be read from the records produced by pens 32 and 34; the record of the pen 33 being considered conclusive as a manifestation of the code signal of an initiating station only when such record is produced without concurrent records of the other pens (as would be the case during the actuation of a short-circuited station).

Should several or all of the initiating stations be concurrently actuated, the actuated station connected in the circuit nearest to the central office terminal 28 would be responded to by relay B, during the operation of such station, to the exclusion of all other stations; and the actuated station connected in the circuit nearest to the central office terminal 29 would be responded to by relay D, during the operation of such station, to the exclusion of all other stations.

For example, if stations H, I and J are simultaneously actuated, the initial movement of the code-wheel 39 of station H will establish a ground connection thereat, throughout the duration of which connection the armature of the relay B will be maintained in attracted position regardless of any circuited interruptions which may result from the actuation of stations I and J; and when, after further rotation of the code-wheel 39 of station H, the first tooth of said code-wheel is withdrawn from the path of its contact 40, the current path through said station will be interrupted, and the relay B will be thus rendered unresponsive to circuit closures or groundings incident to the operation of stations I and J. Succeeding teeth of the code-wheel 39 will first close the current path through station H and immediately thereafter close the ground connection through contact 42 thereat, so that, throughout the operation of station H, relay B will be under the control of said station to the exclusion of stations I and J.

For like reasons, relay D will be controlled exclusively by station J during the operation thereof.

In view of the foregoing, it is evident that if more than two stations are actuated at or about the same time, and if such stations act to transmit their respective code signals but once, the complete code signal of one of such stations will be responded to by the relay B, so as to cause a complete and correct manifestation of such code signal by the pen 32, and the relay D would respond to the signal of some other station, so as to cause the complete and correct manifestation thereof by the pen 34. Inasmuch as it is common practice in signal systems of the general type contemplated by Fig. 1 to transmit important signals (such as, for example, fire alarms) four or more times, it is evident that even under the circumstances

of concurrent action of three or more stations, the record of pens 32 and 34 will clearly disclose and repeatedly verify the respective code signals of some two of such 5 actuated stations, although, previous to such manifestations, the signals of one or more previously actuated stations may be interrupted by subsequently actuated stations in the event that such subsequently actuated 10 stations are connected in the circuit nearer to the central office terminals than the previously actuated stations.

In the event that the signal circuit conductors are crossed at the opposite sides of 15 one, more, or all of the initiating stations (as, for example, through the paths indicated by the dotted line 82 or 83) and, while the conductors are thus crossed, if the normal current path is broken at any point thus 20 short-circuited (as at the point 80),—it is evident that the actuation of any initiating station connected in the portion of the signal circuit which is thus both broken and short-circuited will nevertheless be manifested 25 through the response of relay C to the closures to ground incident to the operation of such station.

Should a difference in potential exist in 30 the earth between the central office ground 68 and the ground of any initiating station, at a time when the normal current path is interrupted, as at the point 80, it is evident 35 that such earth potential will not prevent the response of the relay C to ground closures of any actuated initiating station, as 40 might be the case if a direct current source of energy was employed, as in prior systems.

Referring to Fig. 2, the primary coils 45 221, 222 and 223 are shown connected in delta to the alternating current three-phase generator A², the corresponding secondary coils 231, 232 and 233 are connected in delta to the signal circuit terminals 25, 26 and 27, and will therefore operate through conductors 50 52, 63 and 66 as already described in connection with Fig. 1.

In Fig. 3 the primary coils 321, 322 and 55 323 are shown in star or Y-connection with the three-phase generator A³, while the secondary coils 331, 332 and 333 are correspondingly connected to the signal circuit 60 terminals 25, 26 and 27.

In Fig. 4 an alternating current source 65 A⁴, is shown connected to the primary coil 421 of a suitable transformer, furthermore one lead from said source is also connected to the signal circuit terminal 25 and the other lead from said source is connected to the signal circuit terminal 26. One lead from the secondary coil 431 of such transformer is connected to the signal circuit terminal 26, and the other lead from said coil is connected to the signal circuit terminal 27. The core of such transformer is so proportioned that the primary and secondary

phases are interposed, being, for example, 120° apart. It is evident that the potential of the generator A⁴ will be applied between terminals 25 and 26, and that a corresponding potential will be applied by the secondary coil 431 between the terminals 26 and 27. It is further evident that the potential applied by the secondary coil 431 will be out of phase with that of the generator A⁴. It is believed that the action of the current 70 source arrangement shown in Fig. 4, in connection with a signal system such as shown in Fig. 1, will be obvious to those skilled in this art, and same will therefore not be further described herein. 75

It is evident that the arrangement indicated by Fig. 4 may not be suited to all conditions under which the current source arrangements of Figs. 1, 2 and 3 may be advantageously applied, as the developed potentials and the effective current values in the various current paths which may be established are likely to differ in much greater degree than in cases of the current source arrangements of Figs. 1, 2 and 3. 80 90

Referring to Fig. 5,—a divided battery a, a is connected between terminals 25 and 27, one end of the secondary coil 531 being connected intermediate the ends of said battery, and the other end of said coil being 95 connected to the signal circuit terminal 26, said coil 531 being excited by the primary coil 521 supplied by the single-phase alternating current source A⁵.

In the operation of this arrangement, in 100 connection with a signal system such as that shown in Fig. 1;—it is evident that, under normal conditions, the direct current developed by the battery a, a will flow through relay B, initiating stations F, G, H, I and J, 105 and the relay D, between terminals 25 and 27; and that said relays will therefore respond to breaks and closures of said current path in the manner already described.

The effective electromotive force of the 110 coil 531 should be substantially the same as that of the battery a, a,—hence the establishment of a ground connection at any one of the initiating stations will permit a flow of alternating current through the relay C, 115 and thereby cause the energization thereof. Such alternating current flow will have presented thereto a divided current path including relays B and D, respectively; however, because of the direct current electromotive 120 force of the battery a, a, the alternating current will tend to divide, flowing alternately through relays B and D, as determined by the assisting or opposing battery current flow, and thus will transform the normal, 125 steady direct current flow through these relays into pulsating currents, the mean effective value of such pulsating currents being substantially the same as the normal steady current flow therethrough. 130

It will be apparent that either part of the battery a , a may be employed alone, without destroying the operability of the arrangement shown in Fig. 5.

- 5 In the event of the application of the arrangement of Fig. 5 to the system shown in Fig. 1 with but one of the parts of the battery a , a ; it is evident that the normal current flow will be supplied by such battery a ,
 10 and that, whenever the ground connection of any initiating station became effective, the transformer coil 531 will cause an alternating current flow through the relay C and the ground connections, and that, during flow
 15 of such current in one direction, the direct current flow from battery a will merge therewith, and during current flow in the opposite direction said battery will act in opposition thereto. As a result of such alternate co-operation
 20 and opposition of the battery current, the flow through relays B and D will be of a pulsating character during such alternating current flow, and under many circumstances it might be found to be more difficult to so proportion the various parts
 25 of the system as to assure a desirable degree of equivalency in the effectiveness of the currents which would flow through the various paths if the battery a is not divided than
 30 if arranged as shown in Fig. 5.

In Fig. 6, the single-phase alternating current source A^e is shown connected to the primary coil 621 of a transformer, one end of the secondary coil 622 of such transformer
 35 being connected through the non-inductive resistance 90 to the signal circuit terminal 25, and the other end of said coil being connected through the inductive resistance 91 to the terminal 27, and the terminal 26 being
 40 connected to said coil intermediate the ends thereof.

In this arrangement it is evident that, under normal conditions, there will be no current flow through the path including conductor 65, terminal 26 and conductor 66; and that the current flow through the normal path will traverse resistances 90 and 91, the character of which will tend to develop a difference in phase between the current flowing through the resistance 90 and the conductor 52 and that flowing through the resistance 91 and the conductor 63; which tendency will serve to restrict such current flow to a substantial extent.

55 If now a ground connection is established at any initiating station of a signal circuit connected to the terminals 25, 26 and 27 of Fig. 6, in the manner indicated by Fig. 1, the current flow through resistance 90 and
 60 91 will assume a difference in phase corresponding to the difference in the inductive effect of such resistances, and thereby set up a current flow through relay C to cause the energization thereof.

65 From the foregoing it will be apparent

that the current source arrangement shown in Fig. 6 will operate similarly to that shown in Fig. 1, as already described, except for the fact that it may be very difficult to proportion the resistance and inductance of 90 70 and 91 so as to assure the degree of uniformity of current flow through the various paths which may be attained under differing conditions in a system the current source of which is arranged in accordance with other 75 figures of the accompanying drawings.

The arrangement of Fig. 7 is suited for use in cases when it is not deemed expedient to employ an alternating current source.

In accordance with this arrangement a 80 primary or secondary battery is supplied, comprising the three groups of cells a^1 , a^2 and a^3 ; which groups are connected in series one with another.

Group a^1 and a^3 should preferably contain such number of cells as to afford substantially the same effective voltage, which voltage should suitably exceed that of group a^2 , for reasons to be hereinafter more fully explained, while group a^2 should contain 90 such number of cells as to provide a voltage suitable for the normal current path.

In accordance with this arrangement, relays B and D may be of direct current type, and are arranged in a manner corresponding 95 to that indicated by Fig. 1. Instead of employing relay C in accordance with Fig. 1, relay c is provided with two windings one end of one of said windings being connected to the free terminal of battery group a^1 , and 100 one end of the other of said windings being connected to the free terminal of battery group a^3 . These windings being so connected that, should the remaining ends thereof be connected together, the flow of current 105 therethrough will co-operate to energize the magnet of said relay.

Said remaining ends of the respective coils of the relay c are connected through a pole-changer P with the ground 68'. 110

The pole-changer P is shown comprising a magnet 92 whose armature 93 is connected through the conductor 94 to the ground 68', the front and back stops of said armature being connected through the conductors 95 115 and 96 to respective windings of the relay c.

To obtain best results, the condensers 97 and 98 should be connected between the ground conductor 94 and the conductors 95 120 and 96, respectively, so as to bridge the break gaps between the armature 93 and the front and back stops thereof.

The battery 99 is connected through the vibrating interrupter 100 with the winding 125 of the magnet 92, so that the armature 93 will be caused to vibrate between the front and back stops thereof.

The arrangement of the pole-changer mechanism P is shown for convenience of 130

illustration, but forms no part of this invention, and it is evident that any one of many other wellknown forms of automatic pole-changers may be substituted for that shown 5 and just described.

The conductors 44 and 45 communicate with the magnet 36 and the battery 38, respectively, as more fully shown in Fig. 1.

It should be understood that batteries 38 10 and 99 are shown as being independent of one another, and independent of the main signal circuit current source, merely in the interests of convenience and clearness of illustration.

15 In actual practice,—the current for the operation of the register E may, if desired, be secured from the current source provided for the signal circuit; and the energy for the pole-changer P may, if desired, be secured from all or part of the battery groups a^1 , a^2 and a^3 .

Signal circuit terminals 25 and 27 are connected to the respective terminals of battery group a^2 .

20 25 The operation of the arrangement shown in Fig. 7 is as follows: The pole-changer P operates constantly, thus alternately charging and discharging the condensers 97 and 98, and thereby developing a slight pulsating current flow through the windings of the relay c, which current flow is insufficient to effectively attract the armature of said relay.

25 30 Battery group a^2 is causing a steady direct current flow through the normal signal circuit current path between terminals 25 and 27, and thus causing effective energization of relays B and D.

35 40 Should the ground connection of any initiating station be now established, it is evident that pulsating current flows would be set up through both windings of the relay c, corresponding pulsations in opposite directions would be set up in the conductors 52 and 63, although the mean effective current flow in both of said conductors would be substantially unchanged. As a result of the pulsating energization of the magnet of relay c, the armature of said magnet will 45 move to its front stop and thus cause the energization of magnet 36 to actuate pen 33 (see Fig. 1).

45 50 From the foregoing it will be apparent that the response of relays B, c and D to all normal and abnormal circuit conditions will be the same for the current source arrangement shown by Fig. 7 as that hereinbefore more fully described in connection with Fig. 1.

55 60 The purpose of employing battery groups a^1 and a^3 is to cause, when the ground connection of any initiating station is closed, the development of such pulsating current flows as will be substantially equal in effectiveness to the normal steady current

flow through the usual single current path. It will be understood by those skilled in this art that under certain varieties of operating conditions and in certain varieties of circuit arrangement the potentials of battery groups such as a^1 and a^3 may be substantially less than that of groups such as a^2 , and that, under other conditions and arrangement, either one or both of the groups such as a^1 and a^3 may be dispensed with, 70 the ends of the windings of relay c being then connected directly to the terminals of a battery group such as a^2 .

75 In certain cases, sufficiently effective results may be obtained without employing the condensers 97 and 98, but, ordinarily, the use of these condensers will improve the operating conditions enough to warrant supplying them.

80 85 In the light of the foregoing examples, many other current source arrangements will suggest themselves to those skilled in this art in carrying out the general spirit of this invention, and although certain parts of the arrangements shown herewith form 90 features of this invention, the broad feature of this invention is not limited to any such arrangements.

85 90 The aspect of this invention which is shown in Fig. 7 is not herein specifically claimed, as same forms the subject matter of my co-pending application, Serial No. 666,744, filed October 5th, 1923, as a division hereof.

95 100 What I claim herein and desire to secure by Letters Patent of the United States is:

1. In a signal system,—a normally closed signal circuit loop, a common return conductor associated therewith, and means for applying a suitable electromotive force between the respective ends of said loop and for applying an electromotive force of substantially equivalent mean effectiveness alternately between said loop ends and said conductor. 110

105 115 2. In a signal system,—a normally closed signal circuit loop, a common return conductor associated therewith, a manifesting device to one terminal of which said conductor is connected, and means for applying a suitable electromotive force between the respective ends of said loop and for applying an electromotive force of substantially equivalent mean effectiveness alternately between said loop ends and the other terminal of said device. 120

115 125 3. In a signal system,—a normally closed signal circuit loop serially including manifesting means, a common return conductor associated with said loop, and means for applying a suitable electromotive force between the ends of said loop and for applying an electromotive force of substantially equivalent mean effectiveness alternately between said loop ends and said conductor. 130

4. In a signal system,—a normally closed signal circuit loop including manifesting means at the ends thereof, a common return conductor associated with said loop, and means for applying a suitable electromotive force between the respective ends of said loop and for applying an electromotive force of substantially equivalent mean effectiveness alternately between said loop ends and said conductor.
5. In a signal system,—a normally closed signal circuit loop including manifesting means, a common return conductor associated with said loop, a manifesting device to one terminal of which said conductor is connected, and means for applying a suitable electromotive force between the respective ends of said loop and for applying an electromotive force of substantially equivalent mean effectiveness alternately between said loop ends and the other terminal of said device.
6. In a signal system,—a normally closed signal circuit loop including manifesting means at the ends thereof, a common return conductor associated with said loop, a manifesting device to one terminal of which said conductor is connected, and means for applying a suitable electromotive force between the respective ends of said loop and for applying an electromotive force of substantially equivalent mean effectiveness alternately between said loop ends and the other terminal of said device.
7. In a signal system,—a circuit having signal initiating stations and manifesting means suitably connected thereto, a common return conductor associated with said circuit, and means for applying a suitable electromotive force between the ends of said circuit and for applying an electromotive force of substantially equivalent mean effectiveness alternately between said circuit ends and said conductor.
8. In a signal system,—a circuit having manifesting devices connected at the ends thereof, signal initiating stations suitably connected to said circuit, a common return conductor associated with said circuit, and means for applying a suitable electromotive force between the respective ends of said circuit and for applying an electromotive force of substantially equivalent mean effectiveness alternately between said circuit ends and said conductor.
9. In a signal system,—a circuit having signal initiating stations and manifesting means suitably connected thereto, a common return conductor associated with said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.
10. In a signal system,—a circuit having signal initiating stations suitably connected thereto, manifesting means connected at the ends of said circuit, a common return conductor associated with said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.
11. In a signal system,—a circuit having manifesting means and signal initiating stations suitably connected thereto, said stations each comprising means for formulating a code signal, a common return conductor associated with said circuit, and means for applying a suitable electromotive force between the respective ends of said circuit and for applying an electromotive force of substantially equivalent mean effectiveness alternately between said circuit ends and the other terminal of said device.
12. In a signal system,—a circuit having manifesting devices included at the ends thereof, signal initiating stations suitably connected to said circuit and each comprising means for formulating a code signal, a common return conductor associated with said circuit, and means for applying a suitable electromotive force between the respective ends of said circuit and for applying an electromotive force of substantially equivalent mean effectiveness alternately between said circuit ends and said conductor.
13. In a signal system,—a circuit having manifesting means and signal initiating stations suitably connected thereto, said stations each comprising means for formulating a code signal, a common return conductor associated with said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.
14. In a signal system,—a circuit having signal initiating stations suitably connected thereto and each comprising means for formulating a code signal, manifesting means included at the ends of said circuit, a common return conductor associated with said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.

lent mean effectiveness alternately between such circuit ends and the other terminal of said device.

15. In a signal system,—a circuit having an associated common return conductor and connecting signal-initiating stations and manifesting means, said stations each comprising means for governing the effectiveness of a connection between said conductor and said circuit, and means for applying a suitable electromotive force between the ends of said circuit and for applying an electromotive force of substantially equivalent mean effectiveness alternately between said circuit ends and said conductor.

16. In a signal system,—a circuit having an associated common return conductor and including manifesting devices at the ends thereof, signal initiating stations suitably connected to said circuit and each comprising means for governing the effectiveness of a connection between said conductor and said circuit, and means for applying a suitable electromotive force between the respective ends of said circuit and for applying an electromotive force of substantially equivalent mean effectiveness alternately between said circuit ends and said conductor.

17. In a signal system,—a circuit having an associated common return conductor and connecting signal initiating stations and manifesting means, said stations each comprising means for governing the effectiveness of a connection between said conductor and said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.

18. In a signal system,—a circuit having an associated common return conductor and including manifesting means at the ends thereof, signal initiating stations suitably connected to said circuit and each comprising means for governing the effectiveness of a connection between said conductor and said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.

19. In a signal system,—a circuit having an associated common return conductor and connecting signal initiating stations and manifesting means, said stations each comprising means for formulating a code signal and for governing the effectiveness of a

connection between said conductor and said circuit, and means for applying a suitable electromotive force between the respective ends of said circuit and for applying an electromotive force of substantially equivalent mean effectiveness alternately between said circuit ends and said conductor.

20. In a signal system,—a circuit having an associated common return conductor and including manifesting devices at the ends thereof, signal initiating stations suitably connected to said circuit and each comprising means for formulating a code signal and for governing the effectiveness of a connection between said conductor and said circuit, and means for applying a suitable electromotive force between the respective ends of said circuit and for applying an electromotive force of substantially equivalent mean effectiveness alternately between said circuit ends and said conductor.

21. In a signal system,—a circuit having an associated common return conductor and connecting signal initiating stations and manifesting means, said stations each comprising means for formulating a code signal and for governing the effectiveness of a connection between said conductor and said circuit, a manifesting device to one terminal of which said conductor is connected, and means for applying a suitable electromotive force between the respective ends of said circuit and for applying an electromotive force of substantially equivalent mean effectiveness alternately between said circuit ends and the other terminal of said device.

22. In a signal system,—a circuit having an associated common return conductor and including manifesting means at the ends thereof, signal initiating stations suitably connected to said circuit and each comprising means for formulating a code signal and for governing the effectiveness of a connection between said conductor and said circuit, a manifesting device to one terminal of which said conductor is connected, and means for applying a suitable electromotive force between the respective ends of said circuit and for applying an electromotive force of substantially equivalent mean effectiveness alternately between such circuit ends and the other terminal of said device.

23. In a signal system,—a normally closed signal circuit loop and means for applying a suitable electromotive force between the respective ends of said loop and for applying an electromotive force of substantially equivalent mean effectiveness alternately between said loop ends and the ground.

24. In a signal system,—a normally closed signal circuit loop, a manifesting device one terminal of which is grounded, and means for applying a suitable electromotive force between the respective ends of said loop

and for applying an electromotive force of substantially equivalent mean effectiveness alternately between said loop ends and the other terminal of said manifesting device.

25. In a signal system,—a normally closed signal circuit loop including manifesting means at the ends thereof, a manifesting device one terminal of which is grounded, and
10 means for applying a suitable electromotive force between the respective ends of said loop and for applying an electromotive force of substantially equivalent mean effectiveness alternately between said loop ends
15 and the other terminal of said device.

26. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a normally closed signal circuit loop
20 the respective ends of which are connected to two of said terminals, and a common return conductor associated with said loop and connected to the third of said terminals.

27. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a normally closed signal circuit loop the respective ends of which are connected to two of said terminals, a common return conductor associated with said loop, and a manifesting device connected between said conductor and the third of said terminals.

28. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a normally closed signal circuit loop serially including manifesting means, the respective ends of said loop connected to two of said terminals, and a common return conductor associated with said loop and connected to the third of said terminals.

29. In a signal system,—current supply mechanism having three terminals and comprising means for applying a suitable electromotive force between two of said terminals and for applying an electromotive force of substantially equivalent mean effectiveness alternately between such two and the third of said terminals,—in combination

with a normally closed signal circuit loop, manifesting devices through which the respective ends of said loop are connected to two of said terminals, and a common return conductor associated with said loop and connected to the third of said terminals.

30. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a normally closed signal circuit loop including manifesting means, the respective ends of said loop connected to two of said terminals, a common return conductor associated with said loop, and a manifesting device connected between said conductor and the third of said terminals.

31. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a normally closed signal circuit loop including manifesting means at the ends thereof, the respective ends of said loop connected to two of said terminals, a common return conductor associated with said loop, and a manifesting device connected between said conductor and the third of said terminals.

32. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a circuit having signal initiating stations and manifesting means suitably connected thereto, the respective ends of said circuit connected to two of said terminals, and a common return conductor associated with said circuit and connected to the third of said terminals.

33. In a signal system,—current supply mechanism having three terminals and comprising means for applying a suitable electromotive force between two of said terminals and for applying an electromotive force of substantially equivalent mean effectiveness alternately between such two and the third of said terminals,—in combination with a circuit having signal initiating stations suitably connected thereto, manifesting devices through which the respective ends of said circuit are connected to two of said terminals, and a common re-

- turn conductor associated with said circuit and connected to the third of said terminals.
34. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit having signal initiating stations and manifesting means suitably connected thereto, the respective ends of said circuit connected to two of said terminals, a common return conductor associated with said circuit, and a manifesting device connected between said conductor and the third of said terminals.
35. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit having signal initiating stations suitably connected thereto, a common return conductor associated with said circuit, and manifesting devices two of which are connected between the respective ends of said circuit and two of said terminals and another of which is connected between the third of said terminals and said conductor.
36. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit having manifesting means and signal initiating stations suitably connected thereto, said stations each comprising means for formulating a code signal, the respective ends of said circuit connected to two of said terminals, and a common return conductor associated with said circuit and connected to the third of said terminals.
37. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit having signal initiating stations suitably connected thereto and each comprising means for formulating a code signal, manifesting devices through
- which the respective ends of said circuit are connected to two of said terminals, and a common return conductor associated with said circuit and connected to the third of said terminals.
38. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit having manifesting means and signal initiating stations suitably connected thereto, said stations each comprising means for formulating a code signal, the respective ends of said circuit connected to two of said terminals, a common return conductor associated with said circuit, and a manifesting device connected between said conductor and the third of said terminals.
39. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit having signal initiating stations suitably connected thereto and each comprising means for formulating a code signal, a common return conductor associated with said circuit, and manifesting devices two of which are connected between the respective ends of said circuit and two of said terminals and another of which is connected between the third of said terminals and said conductor.
40. In a signal system;—current supply mechanism having three terminals and comprising means for applying a suitable electromotive force between two of said terminals and for applying an electromotive force of substantially equivalent mean effectiveness alternately between such two and the third of said terminals,—in combination with a circuit connecting signal initiating stations and manifesting means, said stations each comprising means for governing the effectiveness of a connection between said circuit and a common return conductor, the respective ends of said circuit connected to two of said terminals, and a common return conductor for said stations, said conductor connected to the third of said terminals.
41. In a signal system;—current supply mechanism having three terminals and comprising means for applying a suitable electromotive force between two of said terminals and for applying an electromotive force of substantially equivalent mean ef-

fectiveness alternately between such two and the third of said terminals,—in combination with a circuit connecting signal initiating stations, said stations each comprising 5 means for governing the effectiveness of a connection between said circuit and a common return conductor, manifesting devices through which the respective ends of said circuit are connected to two of said terminals, and a common return conductor for 10 said stations, said conductor connected to the third of said terminals.

42. In a signal system;—current supply mechanism having three terminals and comprising 15 means for applying a suitable electromotive force between two of said terminals and for applying an electromotive force of substantially equivalent mean effectiveness alternately between such two and the third of said terminals,—in combination 20 with a circuit having an associated common return conductor and connecting signal initiating stations and manifesting means, said stations each comprising means 25 for governing the effectiveness of a connection between said conductor and said circuit, the respective ends of said circuit connected to two of said terminals, and a manifesting device connected between said 30 conductor and the third of said terminals.

43. In a signal system;—current supply mechanism having three terminals and comprising 35 means for applying a suitable electromotive force between two of said terminals and for applying an electromotive force of substantially equivalent mean effectiveness alternately between such two and the third of said terminals,—in combination 40 with a circuit having an associated common return conductor and connecting signal initiating stations, said stations each comprising means for governing the effectiveness of a connection between said conductor and said circuit, and manifesting devices 45 two of which are connected between the respective ends of said circuit and two of said terminals and another of which is connected between the third of said terminals and said conductor.

44. In a signal system;—current supply mechanism having three terminals and comprising 50 means for applying a suitable electromotive force between two of said terminals and for applying an electromotive force of substantially equivalent mean effectiveness alternately between such two and the third of said terminals,—in combination 55 with a circuit having an associated common return conductor and connecting signal initiating stations and manifesting means, said stations each comprising means for formulating 60 a code signal and for governing the effectiveness of a connection between said conductor and said circuit, the respective ends 65 of said circuit connected to two of said

terminals, and said conductor connected to the third of said terminals.

45. In a signal system;—current supply mechanism having three terminals and comprising 70 means for applying a suitable electromotive force between two of said terminals and for applying an electromotive force of substantially equivalent mean effectiveness alternately between such two and the third of said terminals,—in combination 75 with a circuit connecting signal initiating stations, said stations each comprising means for formulating a code signal and for governing the effectiveness of a connection between said circuit and a common return 80 conductor, manifesting devices through which the respective ends of said circuit are connected to two of said terminals, and a common return conductor for said stations, said conductor connected to the third of 85 said terminals.

46. In a signal system;—current supply mechanism having three terminals and comprising 90 means for applying a suitable electromotive force between two of said terminals and for applying an electromotive force of substantially equivalent mean effectiveness alternately between such two and the third of said terminals,—in combination 95 with a circuit having an associated common return conductor and connecting signal initiating stations and manifesting means, said stations each comprising means for formulating a code signal and for governing the effectiveness of a connection between said 100 conductor and said circuit, the respective ends of said circuit connected to two of said terminals, and a manifesting device connected between said conductor and the third of 105 said terminals.

47. In a signal system;—current supply mechanism having three terminals and comprising 110 means for applying a suitable electromotive force between two of said terminals and for applying an electromotive 115 force of substantially equivalent mean effectiveness alternately between such two and the third of said terminals,—in combination with a circuit having an associated common return conductor and connecting signal initiating stations, said stations each comprising means for formulating a code signal and for governing the effectiveness of a connection between said conductor and said circuit, and manifesting devices two of which are connected between the respective ends of said circuit and two of said terminals and another of which is connected between the third of said terminals and said conductor.

48. In a signal system;—current supply mechanism having three terminals, one of which terminals is grounded, said mechanism comprising means for applying a suitable electromotive force between two of said terminals and for applying an electromotive 125 130

force of substantially equivalent mean effectiveness alternately between such two and the third of said terminals,—in combination with a normally closed signal circuit loop 5 the respective ends of which are connected to the ungrounded terminals of said mechanism.

49. In a signal system,—current supply mechanism having three terminals and comprising means for applying a suitable electromotive force between two of said terminals and for applying an electromotive force of substantially equivalent mean effectiveness alternately between such two and 10 the third of said terminals,—in combination with a normally closed signal circuit loop the respective ends of which are connected to two of the terminals of said mechanism, and a manifesting device connected 15 between the other of said terminals and the ground.

50. In a signal system,—current supply mechanism having three terminals and comprising means for applying a suitable electromotive force between two of said terminals and for applying an electromotive force of substantially equivalent mean effectiveness alternately between such two and the third of said terminals,—in combination 20 with a normally closed signal circuit loop, and manifesting devices two of which are connected between the respective ends of said loop and two of said terminals and another of which is connected between the 25 third of said terminals and the ground.

51. In a signal system,—a normally closed signal circuit loop and a common return conductor associated therewith, in combination with a polyphase current supply source 40 two of the phases of which are connected to the respective ends of said loop and a third phase of which is connected to said conductor.

52. In a signal system,—a normally closed signal circuit loop, a common return conductor associated therewith, and a manifesting device to one terminal of which said conductor is connected, in combination with 45 a polyphase current supply source two of the phases of which are connected to the respective ends of said loop and a third phase of which is connected to the other terminal of said device.

53. In a signal system,—a normally closed signal circuit loop serially including manifesting means, and a common return conductor associated with said loop, in combination with a polyphase current supply source two of the phases of which are 50 connected to the respective ends of said loop and a third phase of which is connected to said conductor.

54. In a signal system,—a normally closed signal circuit loop including manifesting means at the ends thereof, and a common

return conductor associated with said loop, in combination with a polyphase current supply source two of the phases of which are connected to the respective ends of said loop and a third phase of which is connected to said conductor. 70

55. In a signal system,—a normally closed signal circuit loop including manifesting means, a common return conductor associated with said loop, and a manifesting device to one terminal of which said conductor is connected, in combination with a polyphase current supply source two of the phases of which are connected to the respective ends of said loop and a third phase of which is connected to the other terminal of said device. 75

56. In a signal system,—a normally closed signal circuit loop including manifesting means at the ends thereof, a common return conductor associated with said loop, and a manifesting device to one terminal of which said conductor is connected, in combination with a polyphase current supply source two of the phases of which are connected to the respective ends of said loop and a third phase of which is connected to the other terminal of said device. 80

57. In a signal system,—a circuit having signal initiating stations and manifesting means suitably connected thereto, and a common return conductor associated with said circuit, in combination with a polyphase current supply source two of the phases of which are connected to the respective ends of said circuit and a third phase of which is connected to said conductor. 85

58. In a signal system,—a circuit having manifesting devices connected at the ends thereof, signal initiating stations suitably connected to said circuit, and a common return conductor associated with said circuit, in combination with a polyphase current supply source two of the phases of which are connected to the respective ends of said circuit and a third phase of which is connected to said conductor. 90

59. In a signal system,—a circuit having signal initiating stations and manifesting means suitably connected thereto, a common return conductor associated with said circuit, and a manifesting device to one terminal of which said conductor is connected, in combination with a polyphase current supply source two of the phases of which are connected to the respective ends of said circuit and a third phase of which is connected to the other terminal of said device. 100

60. In a signal system,—a circuit having signal initiating stations suitably connected thereto, manifesting means connected at the ends of said circuit, a common return conductor associated with said circuit, and a manifesting device to one terminal of which said conductor is connected, in combination 105

120

125

130

with a polyphase current supply source two of the phases of which are connected to the respective ends of said circuit and a third phase of which is connected to the other terminal of said device.

61. In a signal system,—a circuit having manifesting means and signal initiating stations suitably connected thereto, said stations each comprising means for formulating

10 ing a code signal, and a common return conductor associated with said circuit, in combination with a polyphase current supply source two of the phases of which are connected to the respective ends of said circuit and a third phase of which is connected to said conductor.

62. In a signal system,—a circuit having manifesting devices included at the ends thereof, signal initiating stations suitably 20 connected to said circuit and each comprising means for formulating a code signal, and a common return conductor associated with said circuit, in combination with a polyphase current supply source two of the 25 phases of which are connected to the respective ends of said circuit and a third phase of which is connected to said conductor.

63. In a signal system,—a circuit having 20 manifesting means and signal initiating stations suitably connected thereto, said stations each comprising means for formulating a code signal, a common return conductor associated with said circuit, and a manifesting device to one terminal of which said conductor is connected, in combination with a polyphase current supply source two of the phases of which are connected to the respective ends of said circuit and a third phase of which is connected to the other terminal of said device.

64. In a signal system,—a circuit having signal initiating stations suitably connected thereto and each comprising means for formulating a code signal, manifesting means included at the ends of said circuit, a common return conductor associated with said circuit, and a manifesting device to one terminal of which said conductor is connected, in combination with a polyphase current supply source of two of the phases of which are connected to the respective ends of said circuit and a third phase of which is connected to the other terminal of said device.

65. In a signal system,—a circuit having an associated common return conductor and connecting manifesting means and signal initiating stations, said stations each comprising means for governing the effectiveness of a connection between said conductor and said circuit, in combination with a polyphase current supply source two of the phases of which are connected to the respective

ends of said circuit and the third phase 65 of which is connected to said conductor.

66. In a signal system,—a circuit having an associated common return conductor and including manifesting devices at the ends thereof, signal initiating stations suitably 70 connected to said circuit and each comprising means for governing the effectiveness of a connection between said conductor and said circuit, in combination with a polyphase current supply source two of the 75 phases of which are connected to the respective ends of said circuit and a third phase of which is connected to said conductor.

67. In a signal system,—a circuit having 80 an associated common return conductor and connecting manifesting means and signal initiating stations, said stations each comprising means for governing the effectiveness of a connection between said conductor and said circuit, and a manifesting device 85 to one terminal of which said conductor is connected, in combination with a polyphase current supply source two of the phases of 90 which are connected to the respective ends of said circuit and a third phase of which is connected to the other terminal of said device.

68. In a signal system,—a circuit having 95 an associated common return conductor and including manifesting means at the ends thereof, signal initiating stations suitably connected to said circuit and each comprising means for governing the effectiveness of a connection between said conductor and said circuit, and a manifesting device to 100 one terminal of which said conductor is connected, in combination with a polyphase current supply source two of the phases of 105 which are connected to the respective ends of said circuit and a third phase of which is connected to the other terminal of said device.

69. In a signal system,—a circuit having an associated common return conductor and connecting manifesting means and signal initiating stations, said stations each comprising means for formulating a code signal and for governing the effectiveness of a connection between said conductor and said circuit, in combination with a polyphase 110 current supply source two of the phases of which are connected to the respective ends of said circuit and a third phase of which is connected to said conductor.

70. In a signal system,—a circuit having 115 an associated common return conductor and including manifesting devices at the ends thereof, signal initiating stations suitably connected to said circuit and each comprising means for formulating a code signal and for governing the effectiveness of a connection between said conductor and said circuit, in combination with a polyphase 120

current supply source two of the phases of which are connected to the respective ends of said circuit and a third phase of which is connected to said conductor.

- 5 71. In a signal system,—a circuit having an associated common return conductor and connecting manifesting means and signal initiating stations, said stations each comprising means for formulating a code signal and for governing the effectiveness of a connection between said conductor and said circuit, and a manifesting device to one terminal of which said conductor is connected, in combination with a polyphase current 10 supply source two of the phases of which are connected to the respective ends of said circuit and a third phase of which is connected to the other terminal of said device.
- 15 72. In a signal system,—a circuit having an associated common return conductor and including manifesting means at the ends thereof, signal initiating stations suitably connected to said circuit and each comprising means for formulating a code signal and 20 for governing the effectiveness of a connection between said conductor and said circuit, and a manifesting device to one terminal of which said conductor is connected, in combination with a polyphase current 25 supply source two of the phases of which are connected to the respective ends of said circuit and a third phase of which is connected to the other terminal of said device.

30 73. In a signal system,—a normally closed signal circuit loop, in combination with a polyphase current supply source two of the phases of which are connected to the respective ends of said loop and a third phase of which is grounded.

35 74. In a signal system,—a normally closed signal circuit loop and a manifesting device one terminal of which is grounded, in combination with a polyphase current supply source two of the phases of which 40 are connected to the respective ends of said loop and a third phase of which is connected to the other terminal of said device.

45 75. In a signal system,—a normally closed signal circuit loop including manifesting means at the ends thereof, and a manifesting device one terminal of which is grounded, in combination with a polyphase current supply source two of the phases of which 50 are connected to the respective ends of said loop and a third phase of which is connected to the other terminal of said device.

55 76. In a signal system,—a normally closed signal circuit loop, a common return conductor associated therewith, and means for applying a suitable electromotive force between the respective ends of said loop and for applying an electromotive force alternately between such loop ends and said conductor at such frequency as to be adapted 60 to cause current flow of suitable mean sig-

naling effectiveness between said conductor and either or both of said loop ends.

77. In a signal system,—a normally closed signal circuit loop, a manifesting device, a common return conductor associated with 70 said loop and connected to one terminal of said device, and means for applying a suitable electromotive force between the respective ends of said loop and for applying an electromotive force alternately between such 75 loop ends and the other terminal of said device at such frequency as to be adapted to cause current flow of suitable mean signaling effectiveness between said device and either or both of said loop ends. 80

78. In a signal system,—a normally closed signal circuit loop serially including manifesting means, a common return conductor associated with said loop, and means for applying a suitable electromotive force between the respective ends of said loop and for applying an electromotive force alternately between such loop ends and said conductor at such frequency as to be adapted 85 to cause current flow of suitable mean signaling effectiveness between said conductor and either or both of said loop ends.

79. In a signal system,—a normally closed signal circuit loop including manifesting means at the ends thereof, a common return conductor associated with said loop, and means for applying a suitable electromotive force between the respective ends of said loop and for applying an electromotive force alternately between such loop ends and said conductor at such frequency as to 90 be adapted to cause current flow of suitable mean signaling effectiveness between said conductor and either or both of said loop ends. 95

80. In a signal system,—a normally closed signal circuit loop including manifesting means, a common return conductor associated with said loop, a manifesting device to one terminal of which said conductor is 100 connected, and means for applying a suitable electromotive force between the respective ends of said loop and for applying an electromotive force alternately between such loop ends and the other terminal of said 110 device at such frequency as to be adapted to cause current flow of suitable mean signaling effectiveness between said device and either or both of said loop ends. 115

81. In a signal system,—a normally closed signal circuit loop including manifesting means at the ends thereof, a common return conductor associated with said loop, a manifesting device to one terminal of which said conductor is connected, and means for applying a suitable electromotive force between the respective ends of said loop and for applying an electromotive force alternately between such loop ends and the other 125 terminal of said device at such frequency 130

as to be adapted to cause current flow of suitable mean signaling effectiveness between said device and either or both of said loop ends.

- 5 82. In a signal system,—a circuit having signal initiating stations and manifesting means suitably connected thereto, a common return conductor associated with said circuit, and means for applying a suitable electromotive force between the respective ends of said circuit and for applying an electromotive force alternately between such circuit ends and said conductor at such frequency as to be adapted to cause current 70 flow of suitable mean signaling effectiveness between 75 said conductor and either or both of said circuit ends.
- 10 83. In a signal system,—a circuit having manifesting devices connected at the ends thereof, signal initiating stations suitably connected to said circuit, a common return conductor associated with said circuit, and means for applying a suitable electromotive force between the respective ends of said 80 circuit and for applying an electromotive force alternately between such circuit ends and said conductor at such frequency as to be adapted to cause current 85 flow of suitable mean signaling effectiveness between 90 said conductor and either or both of said circuit ends.
- 15 84. In a signal system,—a circuit having signal initiating stations and manifesting means suitably connected thereto, a common 95 return conductor associated with said circuit, a manifesting device to one terminal of which said conductor is connected, and means for applying a suitable electromotive force between the respective ends of said 100 circuit and for applying an electromotive force alternately between such circuit ends and the other terminal of said device at such frequency as to be adapted to cause current 105 flow of suitable mean signaling effectiveness between 110 said device and either or both of said circuit ends.
- 20 85. In a signal system,—a circuit having signal initiating stations suitably connected thereto, manifesting means connected at the ends of said circuit, a common return conductor associated with said circuit, a manifesting device to one terminal of which said conductor is connected, and means for applying a suitable electromotive force between the respective ends of said 115 circuit and for applying an electromotive force alternately between such circuit ends and the other terminal of said device at such frequency as to be adapted to cause current 120 flow of suitable mean signaling effectiveness between 125 said device and either or both of said circuit ends.
- 25 86. In a signal system,—a circuit having manifesting means and signal initiating stations suitably connected thereto, said sta-

tions each comprising means for formulating a code signal, a common return conductor associated with said circuit, and means for applying a suitable electromotive force between the respective ends of said 70 circuit and for applying an electromotive force alternately between such circuit ends and said conductor at such frequency as to be adapted to cause current flow of suitable mean signaling effectiveness between 75 said conductor and either or both of said circuit ends.

87. In a signal system,—a circuit having manifesting devices included at the ends thereof, signal initiating stations suitably 80 connected to said circuit and each comprising means for formulating a code signal, a common return conductor associated with said circuit, and means for applying a suitable electromotive force between the respective ends of said circuit and for applying an electromotive force alternately between such 85 circuit ends and said conductor at such frequency as to be adapted to cause current flow of suitable mean signaling effectiveness between 90 said conductor and either or both of said circuit ends.

88. In a signal system,—a circuit having manifesting means and signal initiating stations suitably connected thereto, said stations each comprising means for formulating a code signal, a common return conductor associated with said circuit, a manifesting device to one terminal of which said conductor is connected, and means for applying a suitable electromotive force between the respective ends of said circuit and for applying an electromotive force alternately between such circuit ends and the other terminal of said device at such frequency as to be adapted to cause current 100 flow of suitable mean signaling effectiveness between 105 said device and either or both of said circuit ends.

89. In a signal system,—a circuit having signal initiating stations suitably connected thereto and each comprising means for formulating a code signal, manifesting means included at the ends of said circuit, a common return conductor associated with such circuit, a manifesting device to one terminal of which said conductor is connected and means for applying a suitable electromotive force between the respective ends of said circuit and for applying an electromotive force alternately between such circuit ends and the other terminal of said device at such frequency as to be adapted to cause current flow of suitable mean signaling effectiveness between 110 said device and either or both of said circuit ends.

90. In a signal system,—a circuit having an associated common return conductor and connecting manifesting means and signal initiating stations, said stations each com-

prising means for governing the effectiveness of a connection between said conductor and said circuit, and means for applying a suitable electromotive force between the respective ends of said circuit and for applying an electromotive force alternately between such circuit ends and said conductor at such frequency as to be adapted to cause current flow of suitable mean signaling effectiveness between said conductor and either or both of said circuit ends.

91. In a signal system,—a circuit having an associated common return conductor and including manifesting devices at the ends thereof, signal initiating stations suitably connected to said circuit and each comprising means for governing the effectiveness of a connection between said conductor and said circuit, and means for applying a suitable electromotive force between the respective ends of said circuit and for applying an electromotive force alternately between such circuit ends and said conductor at such frequency as to be adapted to cause current flow of suitable mean signaling effectiveness between said conductor and either or both of said circuit ends.

92. In a signal system,—a circuit having an associated common return conductor and connecting manifesting means and signal initiating stations, said stations each comprising means for governing the effectiveness of a connection between said conductor and said circuit, a manifesting device to one terminal of which said conductor is connected, and means for applying a suitable electromotive force between the respective ends of said circuit and for applying an electromotive force alternately between such circuit ends and the other terminal of said device at such frequency as to be adapted to cause current flow of suitable mean signaling effectiveness between said device and either or both of said circuit ends.

93. In a signal system,—a circuit having an associated common return conductor and including manifesting means at the ends thereof, signal initiating stations suitably connected to said circuit and each comprising means for governing the effectiveness of a connection between said conductor and said circuit, a manifesting device to one terminal of which said conductor is connected, and means for applying a suitable electromotive force between the respective ends of said circuit and for applying an electromotive force alternately between such circuit ends and the other terminal of said device at such frequency as to be adapted to cause current flow of suitable mean signaling effectiveness between said device and either or both of said circuit ends.

94. In a signal system,—a circuit having an associated common return conductor and connecting manifesting means and signal

initiating stations, said stations each comprising means for formulating a code signal and for governing the effectiveness of a connection between said conductor and said circuit, and means for applying a suitable electromotive force between the respective ends of said circuit and for applying an electromotive force alternately between such circuit ends and said conductor at such frequency as to be adapted to cause current flow of suitable mean signaling effectiveness between said conductor and either or both of said circuit ends.

95. In a signal system,—a circuit having an associated common return conductor and including manifesting devices at the ends thereof, signal initiating stations suitably connected to said circuit and each comprising means for formulating a code signal and for governing the effectiveness of a connection between said conductor and said circuit, and means for applying a suitable electromotive force between the respective ends of said circuit and for applying an electromotive force alternately between such circuit ends and said conductor at such frequency as to be adapted to cause current flow of suitable mean signaling effectiveness between said conductor and either or both of said circuit ends.

96. In a signal system,—a circuit having an associated common return conductor and connecting manifesting means and signal initiating stations, said stations each comprising means for formulating a code signal and for governing the effectiveness of a connection between said conductor and said circuit, a manifesting device to one terminal of which said conductor is connected, and means for applying a suitable electromotive force between the respective ends of said circuit and for applying an electromotive force alternately between such circuit ends and the other terminal of said device at such frequency as to be adapted to cause current flow of suitable mean signaling effectiveness between said device and either or both of said circuit ends.

97. In a signal system,—a circuit having an associated common return conductor and including manifesting means at the ends thereof, signal initiating stations suitably connected to said circuit and each comprising means for formulating a code signal and for governing the effectiveness of a connection between said conductor and said circuit, a manifesting device to one terminal of which said conductor is connected, and means for applying a suitable electromotive force between the respective ends of said circuit and for applying an electromotive force alternately between such circuit ends and the other terminal of said device at such frequency as to be adapted to cause current flow of suitable mean sig-

naling effectiveness between said device and either or both of said circuit ends.

98. In a signal system,—a normally closed signal circuit loop, and means for applying a suitable electromotive force between the respective ends of said loop and for applying an electromotive force alternately between such loop ends and the ground at such frequency as to be adapted to cause current flow of suitable mean signaling effectiveness between the ground and either or both of said loop ends.

99. In a signal system,—a normally closed signal circuit loop, a manifesting device one terminal of which is grounded, and means for applying a suitable electromotive force between the respective ends of said loop and for applying an electromotive force alternately between such loop ends and the other terminal of said device at such frequency as to be adapted to cause current flow of suitable mean signaling effectiveness between said device and either or both of said loop ends.

100. In a signal system,—a normally closed signal circuit loop including manifesting means at the ends thereof, a manifesting device one terminal of which is grounded, and means for applying a suitable electromotive force between the respective ends of said loop and for applying an electromotive force alternately between such loop ends and the other terminal of said device at such frequency as to be adapted to cause current flow of suitable mean signaling effectiveness between said device and either or both of said loop ends.

101. In a signal system,—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of said terminals, a common return conductor associated with said loop and connected to a third of said terminals.

102. In a signal system,—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of said terminals, a common return conductor associated with said loop, and a manifesting device connected between said conductor and a third of said terminals.

103. In a signal system,—current supply

mechanism having three terminals and comprising two cooperating current sources arranged for action out of phase with one another and serially connected between two of said terminals, the junction between said sources being connected to the third of said terminals,—in combination with a normally closed signal circuit loop serially including manifesting means, the respective ends of said loop connected to two of said terminals, and a common return conductor associated with said loop and connected to a third of said terminals.

104. In a signal system,—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of said terminals, a common return conductor associated with said loop and connected to a third of said terminals, and manifesting means distinctively responsive to current flow in the respective ends of said loop.

105. In a signal system,—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of said terminals, a common return conductor associated with said loop and connected to a third of said terminals, and manifesting means distinctively responsive to current flow in said loop and in said common return conductor.

106. In a signal system,—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of said terminals, a common return conductor associated with said loop and connected to a third of said terminals, and manifesting means distinctively responsive to current flow in the respective ends of said loop and in said common return conductor.

107. In a signal system,—current supply mechanism having three terminals and comprising two cooperating current sources arranged for action out of phase with one another and serially connected between two

- of said terminals, the junction between said sources being connected to the third of said terminals,—in combination with a circuit having signal initiating stations and manifesting means suitably connected thereto, the respective ends of said circuit connected to two of said terminals, and a common return conductor associated with said circuit and connected to a third of said terminals.
108. In a signal system;—current supply mechanism having three terminals and comprising two cooperating current sources arranged for action out of phase with one another and serially connected between two of said terminals, the junction between said sources being connected to a third of said terminals,—in combination with a circuit having signal initiating stations suitably connected thereto, the respective ends of said circuit connected to two of said terminals, a common return conductor associated with said circuit and connected to a third of said terminals, and manifesting means distinctively responsive to current flow in the respective ends of said circuit.
109. In a signal system;—current supply mechanism having three terminals and comprising two cooperating current sources arranged for action out of phase with one another and serially connected between two of said terminals, the junction between said sources being connected to the third of said terminals,—in combination with a circuit having signal initiating stations suitably connected thereto, the respective ends of said circuit connected to two of said terminals, a common return conductor associated with said circuit and connected to a third of said terminals, and manifesting means distinctively responsive to current flow in said circuit and in said conductor.
110. In a signal system;—current supply mechanism having three terminals and comprising two cooperating current sources arranged for action out of phase with one another and serially connected between two of said terminals, the junction between said sources being connected to the third of said terminals,—in combination with a circuit the respective ends of which are connected to two of said terminals, a common return conductor associated with said circuit and connected to a third of said terminals, and manifesting means distinctively responsive to current flow in the respective ends of said circuit and in said conductor.
111. In a signal system;—current supply mechanism having three terminals and comprising two cooperating current sources arranged for action out of phase with one another and serially connected between two of said terminals, the junction between said sources being connected to the third of said terminals,—in combination with a circuit having manifesting means and signal ini-

tiating stations suitably connected thereto, said stations each comprising means for formulating a code signal, the respective ends of said circuit connected to two of said terminals, and a common return conductor associated with said circuit and connected to a third of said terminals.

112. In a signal system;—current supply mechanism having three terminals and comprising two cooperating current sources arranged for action out of phase with one another and serially connected between two of said terminals, the junction between said sources being connected to the third of said terminals,—in combination with a circuit having signal initiating stations suitably connected thereto and each comprising means for formulating a code signal, the respective ends of said circuit connected to two of said terminals, a common return conductor associated with said circuit and connected to a third of said terminals, and manifesting means distinctively responsive to current flow in the respective ends of said circuit.

113. In a signal system;—current supply mechanism having three terminals and comprising two cooperating current sources arranged for action out of phase with one another and serially connected between two of said terminals, the junction between said sources being connected to the third of said terminals,—in combination with a circuit having signal initiating stations suitably connected thereto, said stations each comprising means for formulating a code signal, the respective ends of said circuit connected to two of said terminals, a common return conductor associated with said circuit and connected to a third of said terminals, and manifesting means distinctively responsive to current flow in said circuit and said conductor.

114. In a signal system;—current supply mechanism having three terminals and comprising two cooperating current sources arranged for action out of phase with one another and serially connected between two of said terminals, the junction between said sources being connected to the third of said terminals,—in combination with a circuit having signal initiating stations suitably connected thereto and each comprising means for formulating a code signal, the respective ends of said circuit connected to two of said terminals, a common return conductor associated with said circuit and connected to a third of said terminals, and manifesting means distinctively responsive to current flow in the respective ends of said circuit and in said conductor.

115. In a signal system;—current supply mechanism having three terminals and comprising two cooperating current sources arranged for action out of phase with one another and serially connected between two of

said terminals, the junction between said sources being connected to the third of said terminals,—in combination with a circuit connecting manifesting devices and signal 5 initiating stations, said stations each comprising means for governing the effectiveness of a connection between said circuit and a common return conductor, the respective ends of said circuit connected to two of 10 said terminals, and a common return conductor for said stations, said conductor connected to a third of said terminals.

116. In a signal system;—current supply mechanism having three terminals and comprising 15 two cooperating current sources arranged for action out of phase with one another and serially connected between two of said terminals, the junction between said sources being connected to the third of said 20 terminals,—in combination with a circuit connecting signal initiating stations, said stations each comprising means for governing the effectiveness of a connection between said circuit and a common return conductor, 25 the respective ends of said circuit connected to two of said terminals, a common return conductor for said stations, said conductor connected to a third of said terminals, and manifesting means distinctively responsive 30 to current flow in the respective ends of said circuit.

117. In a signal system;—current supply mechanism having three terminals and comprising 35 two cooperating current sources arranged for action out of phase with one another and serially connected between two of said terminals, the junction between said sources being connected to the third of said terminals,—in combination with a circuit 40 having an associated common return conductor and connecting signal initiating stations, said stations each comprising means for governing the effectiveness of a connection between said conductor and said circuit, the respective ends of said circuit connected to 45 two of said terminals and said conductor connected to a third of said terminals, and manifesting means distinctively responsive to current flow in said circuit and in said 50 conductor.

118. In a signal system;—current supply mechanism having three terminals and comprising 55 two cooperating current sources arranged for action out of phase with one another and serially connected between two of said terminals, the junction between said sources being connected to the third of said terminals,—in combination with a circuit having an associated common return conductor and connecting signal initiating stations, said stations each comprising means for governing the effectiveness of a connection between said conductor and said circuit, the respective ends of said circuit connected to two of said terminals and said 60 65

conductor connected to a third of said terminals, and manifesting means distinctively responsive to current flow in the respective ends of said circuit and in said conductor.

119. In a signal system;—current supply 70 mechanism having three terminals and comprising two cooperating current sources arranged for action out of phase with one another and serially connected between two of said terminals, the junction between said 75 sources being connected to the third of said terminals,—in combination with a circuit having an associated common return conductor and connecting manifesting means 80 and signal initiating stations, said stations each comprising means for formulating a code signal and for governing the effectiveness of a connection between said conductor and said circuit, the respective ends of said circuit connected to two of said terminals, and said conductor connected to a third of said terminals.

120. In a signal system;—current supply mechanism having three terminals and comprising two cooperating current sources arranged for action out of phase with one another and serially connected between two of said terminals, the junction between said sources being connected to the third of said terminals,—in combination with a circuit 95 connecting signal initiating stations, said stations each comprising means for formulating a code signal and for governing the effectiveness of a connection between said circuit and a common return conductor, the 100 respective ends of said circuit connected to two of said terminals, a common return conductor for said stations, said conductor connected to a third of said terminals, and manifesting means distinctively responsive to current flow in the respective ends of said circuit.

121. In a signal system;—current supply mechanism having three terminals and comprising two cooperating current sources 110 arranged for action out of phase with one another and serially connected between two of said terminals, the junction between said sources being connected to the third of said terminals,—in combination with a circuit 11 having an associated common return conductor and connecting signal initiating stations each comprising means for formulating a code signal and for governing the effectiveness of a connection between said conductor and said circuit, the respective ends of said circuit connected to two of said terminals and said conductor connected to a third of said terminals, and manifesting means distinctively responsive to current 12 flow in said circuit and in said conductor.

122. In a signal system;—current supply mechanism having three terminals and comprising two cooperating current sources arranged for action out of phase with one 13

- another and serially connected between two of said terminals, the junction between said sources being connected to the third of said terminals,—in combination with a circuit 5 having an associated common return conductor and connecting signal initiating stations, said stations each comprising means for formulating a code signal and for governing the effectiveness of a connection between said conductor and said circuit, the respective ends of said circuit connected to two of said terminals and said conductor connected to a third of said terminals, and manifesting means distinctively responsive 10 to current flow in the respective ends of said circuit and in said conductor.
123. In a signal system;—current supply mechanism having three terminals, one of which terminals is grounded, said mechanism comprising two cooperating current sources arranged for action out of phase with one another and serially connected between two of said terminals, the junction between said sources being connected to the third of said terminals,—in combination with a normally closed signal circuit loop the respective ends of which are connected to the ungrounded terminals of said mechanism.
124. In a signal system;—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of the terminals of said mechanism, and a manifesting device connected between the other of said terminals and the ground.
125. In a signal system;—current supply mechanism having three terminals and comprising two cooperating current sources arranged for action out of phase with one another and serially connected between two of said terminals, the junction between said sources being connected to the third of said terminals,—in combination with a normally closed signal circuit loop the respective ends of which are connected to two of said terminals, a ground connection connected to a third of said terminals, and manifesting means distinctively responsive to current flow in the respective ends of said circuit and in said ground connection.
126. In a signal system,—a normally closed signal circuit loop, and current supply mechanism comprising means for developing a suitable electromotive force and for applying such force at such frequency of alternation between the respective ends of said loop and between one and the other of said ends and the ground as to be adapted to concurrently cause current flow of suitable mean continuous effectiveness in said loop and between either or both ends thereof and the ground.
127. In a signal system,—a normally closed signal circuit loop, a manifesting device one terminal of which is grounded, and current supply mechanism comprising means for developing a suitable electromotive force and for applying such force at such frequency of alternation between the respective ends of said loop and between one and the other of said ends and the other terminal of said device as to be adapted to concurrently cause current flow of suitable mean continuous effectiveness in said loop and between either or both ends thereof and the other terminal of said device.
128. In a signal system,—a normally closed signal circuit loop, a ground connection, manifesting means comprising electromagnets to individual ones of which said means is distinctively responsive, two of said magnets being included in said loop at the respective ends thereof and the third of said magnets included in said ground connection, and current supply mechanism comprising means for developing a suitable electromotive force and for applying such force at such frequency of alternation between the respective ends of said loop and between one and the other of said ends and the ground as to be adapted to cause effectively continuous energization of said electromagnets either singly or concurrently as to any two or all three thereof.

In witness whereof, I hereunto subscribe my name, this 1st day of November 1919.

C. E. BEACH.
